(57) **CLAIM**

The ornamental design for a solar dandelion light, substantially as shown and described.

DESCRIPTION

FIG. 1 is a top, front and right side perspective view of a solar dandelion light, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a partial enlarged view of FIG. 1.

The broken lines shown in FIG. 7 illustrate the portions of the solar dandelion light that form no part of the claimed design.

The dash-dash broken lines in FIG. 1 define the bounds of the claimed design and form no part thereof.
